UNITED STATES PATENT OFFICE.

WILLIAM J. LUTTON, OF PATERSON, NEW JERSEY, ASSIGNOR TO CROMPTON & KNOWLES
LOOM WORKS, A CORPORATION OF MASSACHUSETTS.

TAKE-UP MECHANISM FOR LOOMS.

No. 882,904.

Specification of Letters Patent. Patented March 24, 1908.

Application filed July 5, 1906. Serial No. 324,768.

To all whom it may concern:

Be it known that I, WILLIAM J. LUTTON, a citizen of the United States, residing at Paterson, in the county of Passaic and State of New Jersey, have invented certain new and useful Improvements in Take-Up Mechanism for Looms, of which the following is a specification.

My invention relates to a take-up mechanism of a loom, and more particularly to that class of take-up mechanisms in which the cloth-roll is rotated through the frictional engagement of a disk fast on the shaft of said cloth-roll, with a driven gear loose on said shaft.

In this class of take-up mechanisms, means are ordinarily provided for manually regulating the degree of frictional engagement between the disk, fast on the shaft of the cloth-roll, and the driven gear loose on said shaft, and forming the friction driving mechanism of the cloth-roll, to adjust the rotary motion of the cloth-roll.

The object of my invention is to improve upon the construction of take-up mechanisms of the class referred to, and to provide an improved take-up mechanism for operating the cloth-roll, which is particularly adapted to be used on looms for weaving silk, or like fabrics and in which the rotary motion of the cloth-roll is automatically adjusted, according to the length of the woven fabric passing over the guide-roll from the take-up roll.

In my improvements I provide means for automatically regulating the friction driving mechanism of the cloth-roll, or the frictional engagement between the disk fast on the shaft of the cloth-roll, and the driven gear loose on said shaft, to adjust the rotary motion of the cloth-roll according to the length of the woven fabric passing over the guide-roll from the take-up roll.

My invention consists in certain novel features of construction of my improvements, as will be hereinafter fully described.

I have only shown in the drawings a detached portion of a loom frame, and of a take-up mechanism embodying my improvements, sufficient to enable those skilled in the art to understand the construction and operation thereof.

Referring to the drawings:—Figure 1 is a front view of a take-up mechanism with my improvements applied thereto, looking in the

direction of arrow *a*, Fig. 2. Fig. 2 is, on an enlarged scale, a section on line 2, 2, Fig. 1, looking in the direction of arrow *b*, same figure, and, Fig. 3 is a section on line 3, 3, Fig. 2, looking in the direction of arrow *a*, same figure.

In the accompanying drawings, 1 are detached portions of the two loom sides or end frames, 2 is the breast-beam extending between said frames; 3 are vertically extending stands secured to the breast-beam at their upper ends, and to the loom side at their lower ends. 4 is the breast-beam roll, journaled in suitable bearings, and over which the woven fabric 5, shown by broken lines in Fig. 2, passes. 6 is a guide-roll for the woven fabric 5, and 7 is the take-up roll, around which the woven fabric 5 passes from the guide-roll 6. From the take-up roll 7 the woven fabric passes over a roll 8 to the cloth-roll 9. All of said rolls except the roll 8, are journaled in suitable bearings on the stands 3.

10 is a ratchet wheel fast on a shaft 11, and is operated by a pawl, not shown, driven from some moving part of the loom in the usual way. A pinion 12, fast on the shaft 11, meshes with and drives a gear 13, and through pinion 14 drives a gear 15 fast on the shaft 7' of the take-up roll 7. On the opposite end of the shaft 7' is a gear 16, which meshes with and drives an intermediate gear 17, which in turn meshes with and drives a gear 18, loose on the shaft 9' of the cloth-roll 9. The cloth-roll 9 has a hand wheel 9" on the end thereof, and the shaft 9' has fast thereon, in this instance secured by a spline 9'', a friction disk 19 having a friction surface 19' thereon, which is adapted to be engaged by the gear 18, see Fig. 3.

All of the above mentioned parts, except the roll 8, may be of the usual and well known construction.

I will now describe my improvements.

The roll 8 has its journal 8' at each end 100 mounted in a hub or boss 20' on an arm 20, which is loosely mounted on a stud 21 on the outer end of a lever 22. There is a lever 22 at each end of the loom, which has a hub 22' loosely mounted on the shaft 7' of the take-up roll 7. Extending down from the boss or hub 20' is a lug 20", which has attached thereto one end of a helically coiled contraction spring 23, the other end of said spring 23 is attached in this instance to an extension 110

22" on the lever 22. The spring 23 acts to yieldingly hold the roll 8 in engagement with the take-up roll 7.

- Extending transversely between the levers 22, is a rod 24, which is attached to said levers 22 to cause them to move together. One end of the rod 24 is extended, see Fig. 1, and has its extreme end 24' reduced, to receive the upper end of a connector or link 25. The lower end of the connector 25 has a rod head 26 adjustably secured thereto, and carrying a pin 26', which is adapted to enter a hole in any one of the projections or knobs 27' on a wheel 27. The wheel 27 has a screw threaded hub 27", see Fig. 3, which is adapted to rotate on the threaded inner end 28' of a collar 28, loosely mounted on the extended reduced end of the shaft 9' of the cloth-roll 9. The outer end of the collar 28 is secured in a hub 29' on an arm 29 secured to the loom frame, see Fig. 1. A helically coiled contraction spring 30 is secured at one end to an extension 22" on each lever 22, and at its other end to a stationary part of the loom frame, and acts to hold the upper end of each lever 22 in its raised position. The wheel 27 bears against a washer 31 loose on the shaft 9', and intermediate the hub of the gear 18 and the hub of the wheel 27, see Fig. 3. The turning of the wheel 27 on the stationary threaded collar 28, toward the gear 18, will, through the collar 31, move the gear 18 into closer frictional engagement with the disk 19. The turning of the wheel 27 in the opposite direction will lessen the frictional engagement of the gear 18 with the disk 19. The rotating of the wheel 27, to vary the friction on the driven gear 18 of the cloth-roll 9, is automatically controlled, through the link 25, lever 22, and the roll 8 journaled in the arms 20 attached to said lever 22.
- When there is too much woven fabric coming off of the take-up roll, the springs 30 will act to draw down the inner ends of the levers 22, and the downward movement of said levers 22, through the link 25, will rotate the wheel 27, and move it toward the gear 18, to increase the friction between said gear 18, and the disk 19, and cause the cloth-roll 9 to turn faster to take up the fabric. In case the woven fabric from the take-up roll 7 is shortened, the tension on the fabric is greater and through the roll 8 being drawn down by the fabric 5, the levers 22 at their outer ends are moved downwardly, against the action of the springs 30, and the inner ends are raised, and through link 25, the wheel 27 is rotated and turned away from the gear 18, to lessen its frictional engagement with the disk 19, and allow the cloth-roll 9 to slip, and not to take up the fabric so rapidly. It will thus be seen, that by means of my mechanism, the degree of frictional engagement between the driven gear 18 and the disk 19 fast on the shaft 9' of the take-up roll 9, is automatically

regulated, according to the length of the fabric passing from the take-up roll.

I preferably provide a movable latch 32, see Fig. 2, or other suitable device, which may be used to hold the outer ends of the two levers 22 and the roll 8 in their lowered position, against the action of the spring 30, to release the friction and allow the goods to be taken from the cloth-roll by hand, or allow the cloth-roll to be turned in either direction. The latch 32 has in this instance a hub 32', mounted on a stand 33 on one side frame 3, and has an engaging end 32" by which it may be raised and lowered, and a projection 32'" to extend over the hub 20" of the arm 20.

It will be understood that the details of construction of my improvements may be varied if desired.

Having thus described my invention, what I claim as new and desire to secure by Letters Patent is:—

1. In the take-up mechanism of a loom, a cloth roll, a rotary take-up roll, two pivoted levers, a roll over which the fabric from said take-up roll passes, said roll carried by said levers and movable therewith, means for holding said roll in yielding engagement with said take-up roll, means for yieldingly holding said levers in their raised position and friction driving mechanism for the cloth-roll, and connections intermediate said levers and said friction driving mechanism, to automatically regulate the rotary motion of the cloth-roll, by the raising and lowering of said levers, and the raising and lowering of the roll carried by said levers.

2. In the take-up mechanism of a loom, a cloth roll, a rotary take-up roll, two pivoted levers, a roll over which the fabric from said take-up roll passes, said roll carried by said levers and movable therewith, means for holding said roll in yielding engagement with said take-up roll, means for yieldingly holding said levers in their raised position and friction driving mechanism for the cloth-roll, and connections intermediate said levers and said friction driving mechanism of the cloth-roll, to automatically regulate the rotary motion by the raising and lowering of said levers, and the raising and lowering of the roll carried by said levers, said connections comprising a connector from said levers to a wheel having a threaded hub and turning on a threaded collar, and said wheel connected with said connector, and adapted to be automatically rotated by the raising and lowering of said levers and the raising and lowering of the roll carried on said levers, to regulate the frictional engagement of the friction driving mechanism of the cloth-roll.

3. In the take-up mechanism of a loom, a cloth roll, a rotary take-up roll, two pivoted levers, a roll over which the fabric from said take-up roll passes, said roll carried by said

levers and movable therewith, means for holding said roll in yielding engagement with said take-up roll, means for yieldingly holding said levers in their raised position and 5 friction driving mechanism for the cloth-roll, and connections intermediate said levers and said friction driving mechanism, to automatically regulate the rotary motion of the cloth-roll by the raising and lowering of said 10 levers, and the raising and lowering of the roll carried by said levers, and movable means for positively holding the outer ends of said levers and the roll supported on said 15 levers, in their lowered position.

4. In the take-up mechanism of a loom, a

rotary take-up roll, two pivoted levers, a roll over which the fabric from said take-up roll passes, said roll carried by said levers and movable therewith, means for holding said roll in yielding engagement with said 20 take-up roll, means for yieldingly holding said levers in their raised position, and movable means for positively holding the outer ends of said levers and the roll supported on said levers, in their lowered position.
